(57) **CLAIM**

The ornamental design for a clip post, as shown and described.

DESCRIPTION

FIG. 1 is a right side perspective view of a clip post showing my new design;

FIG. 2 is a left side elevational view of the clip post seen in FIG. 1, the right side elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The flag shown in dashed lines is included for the purpose of illustrating environment and forms no part of the claimed design.
